UNITED STATES PATENT OFFICE.

JOSEPH DEARWOOD, OF SAULT STE. MARIE, MICHIGAN.

CABINET IRONING BOARD.

Application filed January 28, 1927. Serial No. 164,236.

This invention relates to new and useful improvements in ironing boards and has for its primary object to provide a combined ironing board and cabinet that may be rigidly secured to the wall of the kitchen or disposed within a pocket formed within the wall, with the end in view that the board per se may be swung into the cabinet so as to be out of the way when not required for use.

The invention further aims to provide a board of this character wherein means is provided for supporting the same in horizontal position for use, said means being further adapted for providing a closure for the cabinet when the board is swung upwardly therein.

With the foregoing and other objects in view as the nature of the invention will be better understood, the same comprises the novel form, combination and arrangement of parts hereinafter more fully described, shown in the accompanying drawing and claimed.

In the drawing wherein like numerals of reference indicate corresponding parts throughout all of the views:

Figure 1 is a front elevation of my improved cabinet ironing board.

Figure 2 is a detail longitudinal section thereof, and

Figure 3 is a sectional view disclosing the board per se as swung outwardly of the cabinet, and supported in horizontal position by the means which also affords a door for the cabinet when the board is swung upwardly therein.

Now having particular reference to the drawing, my novel device consists of an open faced cabinet 5 of predetermined size that may be set directly within a pocket in the kitchen wall or that may be equipped at its corners with suitable brackets 6 to permit the same to be rigidly secured to the wall surface as suggested in the drawing.

Pivotedly disposed within this cabinet 5 adjacent the lower end thereof as at 7 is the lower end of an ironing board 8, the forward end of which is tapered at its opposite edges as indicated by the dotted lines in Figure 1. Set within the front side of the cabinet 5 at the upper end thereof are side panels 9—9, the inner edges of which are tapered also as indicated in Figure 1 for a purpose herein-after more fully described.

Hingedly secured to the bottom wall of

the cabinet at the front side thereof as at 10 is the lower end of a board 11 that forms a closure for a portion of the front side of the cabinet when the same is swung upwardly into the position disclosed in Figures 1 and 2. The upper end of this board 11 is tapered at its opposite edges as at 12—12 while hingedly secured to the extreme upper end of this board as at 13 is a supporting board 14 formed at its lower hinged edge with downwardly diverging side legs 15—15 for engagement along the tapered edges 12—12 of the board 11 when the same is swung upwardly in the direction of the arrows in Figure 3. The transverse area of this supporting board 14 is such that the same will snugly fit within the panels 9—9 of the cabinet 5 so as to cooperate with the board 11 in entirely closing the front side 75 of the cabinet after the ironing board 8 has been swung upwardly therein.

The under side of the ironing board 8 is formed adjacent its upper end with a cross channel 8' for receiving the upper edge of the board 14 when the same is disposed perpendicularly with respect to the ironing board so as to prevent the swinging of the supporting board 14 when the same has been properly arranged beneath the ironing board.

It will thus be seen that I have provided a highly novel, simple, and efficient cabinet ironing board that is well adapted for all the purposes heretofore designated, and even though I have herein shown and described the invention as consisting of certain detail structural elements it is nevertheless to be understood that some changes may be made therein without effecting the spirit 95 and scope of the appended claims.

Having thus described the invention, what I claim is:—

1. In a device of the class described, a cabinet open at its front side, an ironing board pivoted at its lower end within the cabinet and adapted to be swung outwardly of the cabinet and downwardly to a horizontal operative position for use, a lower door section hinged transversely at its lower end to the lower end of the cabinet below said board, and being of less length than the cabinet, an upper door section hinged at its lower edge to the upper edge of the lower door section, and being swingable to a position approximately at right angles with respect to the lower door section when in op-

erative position, the upper end of the upper door section supporting the outer end of said board, when in said position, and side legs extending from the lower edge of the upper door section and adapted to engage the floor.

2. In a device of the class described, a cabinet open at its front side, a pair of side panels arranged in the upper end of the open side of the cabinet, an ironing board pivoted at its lower end within the lower portion of the cabinet and disposed inwardly of the side panels, when in a vertical position within the cabinet, said ironing board adapted to swing outwardly and downwardly to a horizontal operative position for use, a lower door section hinged at its lower edge to the lower forward edge of the cabinet, an upper door section hinged at its lower edge

to the upper edge of the lower door section so as to swing downwardly approximately 20 at right angles to the lower door section beneath the ironing board, and side legs extending from the lower edge of the upper door section, whereby said door section may serve as a support for the ironing board 25 when the latter is disposed in a horizontal position, the side edges of the lower door section being cut away at their upper ends to receive the legs of the upper door section when the latter is swung into the plane of 30 the lower door section, said legs and said sections forming a closure for the open side of the cabinet, when not in use.

In testimony whereof I affix my signature.

JOSEPH DEARWOOD.
